FLIER CONSTRUCTION

Michael J. McHale, Scranton, Pa.

Application September 23, 1931, Serial No. 564,664

11 Claims. (Cl. 117—23)

My invention relates to improvements in flier blocks and more particularly to a flier block having a flanged foot adapted for engagement with a bobbin.

- 6 It has been proposed to use flier blocks having either an eccentric foot or two oppositely disposed flanged portions at the bottom of the flier body adapted for engagement with a retaining bushing inserted in the top of a bobbin.
- 10 In addition to the increased cost in preparing the eccentric foot, there is considerable wear on the latter, due to the single point of contact between the foot and the retaining bushing in the bobbin. Since the block must be replaced after 15 the foot has worn away, such installations are expensive to maintain. While flier blocks having two oppositely disposed flanges tend to decrease the cost of maintenance, there is still considerable wear on the flanges. The two-point contact arrangement is further open to the objection that 20 the block will rock, about its two-points of contact with the bushing in the top of the bobbin and this movement, in combination with the oscillation or rotation of the block, produces a resultant 25 force on the flier wire which very often breaks the thread or the wire.

In the prior art devices having an eccentric foot or oppositely disposed flanges, adapted for insertion into bobbins, the foot or opposite flanges 30 are formed integral with the flier body or hub of the body portion. My invention comprehends a flier structure having a replaceable foot member formed integral with the tubular bearing of the block. By means of this arrangement, economies 35 are effected in maintenance of the flier blocks, since the flier body, including the wire retaining means may be used again when the retaining foot member is worn away.

An object of my invention is to provide an improved flier block having retaining means adapted for insertion into bobbins.

Another object of my invention is to provide an improved flier block having a triangular shaped foot member adapted for insertion into bobbins.

45 Yet another object of my invention is to provide an improved flier block having a replaceable foot member, adapted for insertion into bobbins.

Still another object of my invention is to provide an improved flier block having a removable bearing and block retaining means formed integral with the bearing.

With these and other objects in view, which may be incident to my improvements, the invention consists in the parts and combinations to be 55 hereinafter set forth and claimed, with the un-

derstanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

In the drawing like numerals refer to similar parts throughout several views, of which:

Figure 1 is a vertical sectional view, of a bobbin mounted upon a spindle and provided with a flier block and associated retaining bushing.

Fig. 2 is a sectional view along line 2—2 of Figure 1; and

Fig. 3 is a vertical sectional view showing a flier provided with a removable retaining foot.

Referring to the drawing and more particularly to Figure 1, there is shown a bobbin 1 mounted upon a spindle 2, which is tapered to engage the central axis of the bobbin. The spindle is provided at its upper portion with a section 3 of uniform diameter, which section is adapted to support a freely rotatable flier block 4.

The improved flier blocks forming an essential part of the present invention are similar in construction to those shown and claimed in my applications, Serial Nos. 489,401, filed October 17, 1930 and 517,023, filed February 13, 1931 and are distinguished therefrom in that the blocks are provided with a removable foot or flange.

The blocks are provided with any suitable type of flier wire 5, which is retained in or on the block by any suitable means such as, a screw threaded nut 6, the details of which are shown and claimed in my applications above referred to.

The foot member of the flier block 4, is formed with flanges 7 adapted for engagement with a bushing 8 inserted in the top of the bobbin. The flanges are arranged so that the foot member is substantially triangular in shape, the flanges being integral with the hub of the flier body. The bushing 8 is coaxial with the flier block and is provided with a retaining shoulder 9. The spindle 3 passes through the bobbin and the bushing, thus retaining the block in locked position by means of the engagement of the foot member with the retaining shoulder of the bushing.

Referring to Figure 2, it will be seen that the flanges 7 extend back under the retaining shoulder 9, giving a balanced three-point support for

the flier block. By means of the triangular shaped foot, the block is prevented from rocking during rotation or oscillation, whereby excessive strain on the flier wire and thread is prevented. Also by 5 means of the improved foot construction, a substantial bearing surface is provided for engagement with the retaining bushing, with consequent uniform distribution of the bearing forces.

Referring to Figure 3, I have shown an improved 10 flier block 10, having a removable tubular bearing 11. The bearing is provided with a triangular shaped foot comprising flanges 12, and it is further provided with a reduced portion 13 forming a peripheral flange 14 in the body of the bearing.

15 To mount the flier block upon the bearing, the block is passed over the reduced portion 13 and seats on the flange 14. The upper edge 15 of the reduced portion is then turned back or peened, on the inner of the two nested members comprising 20 the flier block. In this manner, the block is securely attached to the bearing so that the block and bearing rotate in unison. When it is desired to remove a foot member from the block, the edge 15 may be turned back slightly and the bearing, 25 together with the foot member, is then easily forced out of the flier block.

It will be understood that the invention comprehends other means for attaching the flier to the bearing; the bearing may be provided with screw 30 threads adapted to engage with the flier block or a bayonet type of joint between the flier block and bearing, may be used.

The improved foot constructions, above described, in combination with the novel flier block 35 construction, permits economies both in manufacturing and operation and are characterized by simplicity of installation and maintenance.

While I have shown and described the preferred 40 embodiment of my invention, I wish it to be understood that I do not confine myself to the precise details of construction herein set forth, by way of illustrations, as it is apparent that many changes and variations may be made therein, by those skilled in the art, without departing from 45 the spirit of the invention, or exceeding the scope of the appended claims.

What I claim is:

1. In a flier for spinning machines, including a 50 body portion, a foot member adapted for insertion into bobbins, said foot being detachably secured to the flier body and rotatable therewith.

2. In a flier for spinning machines, including a body portion, substantially triangular shaped foot adapted for insertion into bobbins, said foot being 55 detachably secured to the flier body and rotatable therewith.

3. In a flier, including a body portion, a removable bearing formed with a foot adapted for insertion into bobbins, said bearing being rigidly attached to the flier body and adapted to rotate 60 therewith.

4. A flier for spinning machines, including a

body portion, a substantially triangular shaped foot comprising circumferentially equi-spaced flanges adapted for insertion into bobbins, said foot being removably attached to the flier body and rotatable therewith.

80

5. In a flier having a centrally apertured body portion, a tubular bearing removably attached to the flier body and formed with a foot adapted for insertion into bobbins, said foot comprising circumferentially equi-spaced flanges rigidly attached to the bearing.

85

6. A flier for spinning machines comprising the combination of a centrally apertured body portion having a removable foot member adapted for insertion into bobbins, said foot being detachably secured to the flier body and separable screw threaded means formed with the flier body adapted to retain a flier wire thereon.

90

7. A flier for spinning machines comprising the combination of a centrally apertured body portion having a removable bearing formed with a foot adapted for insertion into bobbins, said bearing being rigidly attached to the flier body and separable screw threaded means formed with the flier body 100 adapted to retain a flier wire thereon.

95

8. A flier for spinning machines comprising the combination of a centrally apertured body portion having a tubular bearing removably attached thereto, the bearing being provided with a foot adapted for insertion into bobbins, said foot comprising circumferentially equi-spaced flanges attached to the bearing, and separable screw threaded means formed with the flier body 105 adapted to retain a flier wire thereon.

110

9. A flier for spinning machines comprising the combination of a centrally apertured body portion, a tubular member formed with a foot adapted for insertion into bobbins, said member having a reduced portion seated in the central aperture of the body, the tubular member being rigidly attached to the flier and rotatable therewith.

115

10. A flier for spinning machines comprising the combination of a centrally apertured body portion, a tubular member formed with a foot comprising circumferentially equi-spaced flanges adapted for insertion into bobbins, said member having a reduced portion seated in the central aperture of the body, the tubular member being 120 rigidly attached to the flier and rotatable therewith.

125

11. A flier for spinning machines comprising the combination of a centrally apertured body portion, a tubular member formed with a foot adapted for insertion into bobbins, said member having a reduced portion defining a peripheral flange on the body of the member, forming a seat for the flier when the reduced portion is inserted in the central aperture in the body of 130 the flier.
